PACKAGE AND CONTAINER FOR ICE CREAM
AND THE LIKEClarence W. Vogt, Louisville, Ky., assignor, by
mesne assignments, to Vogt Processes, Incor-
porated, Louisville, Ky., a corporation of Dela-
ware

Application August 22, 1932, Serial No. 629,776

9 Claims. (Cl. 206—46)

This invention relates to containers adapted for the shipment and storage of a plurality of individual packages and more particularly to a container adapted to receive a plurality of small packages of ice cream of a size and character to serve as individual portions.

The invention also involves an improved package including the container in combination with the contents arranged in a particular relationship thereto.

The individual portions or packages for which the container is particularly adapted and designed may be such as is disclosed and claimed in my Patent No. 1,906,183, issued April 25, 1933.

One object of the present invention is to provide a shipping package or carrier by means of which a quantity of the individual portions or blocks may be supported in bundles or bulk in a manner to permit storage and transportation, these carriers being such as to permit the easy assembly of the individual packages therein and the easy removal thereof for dispensing purposes.

As an important feature of the present invention, these carriers are very inexpensive to manufacture, easy to assemble, rugged and durable against ordinary handling in storage and transportation, easy to dispense from, and so formed as to effectively protect the contents thereof against tampering during storage and transportation.

As another feature of the present invention, the carrier has a frame structure comprising a substantially strong base and a pair of rigid columns upstanding therefrom and adapted to hold therebetween the material to be carried and to support the weight of a superposed package. Means are provided at the upper ends of said columns to facilitate carrying the package. The frame structure is preferably made from a stiff paper blank having a central portion to serve as a base and end portions bendable to form the upstanding columns.

As another feature of the present invention, the carrier is provided with a handle bar extending across the top of the carrier and normally in position close to the top of the package to permit these carriers to be stacked, and shiftable to spaced relationship with said top to permit the carrying hand to extend thereunder.

As another feature of the present invention, each column of the frame structure comprises a main side wall and a pair of flaps on the edges thereof bent to angular relationship therewith to impart rigidity to the columns, and forming flanges to protect the material to be supported.

As a further important feature of the present invention, there is provided for the individual blocks of ice cream a shipping unit which includes a frame member for supporting the blocks in stacked relationship and an outside covering mounted in telescopic relationship with said frame member and adapted to conceal the contents to form a neat, strong package.

As a further feature one of the columns has attached thereto one end of a wrapper which, after the package is filled, may be drawn tightly around the package and the opposite end secured to said columns to form a tight peripheral supporting wall.

As a further feature, the upper end of one of the columns may have an extension forming a handle.

In the accompanying drawings there are illustrated certain embodiments of my invention.

In these drawings:

Fig. 1 is a perspective view of the package prior to the application of the outer wrapper and handle.

Fig. 2 is a perspective view of the wrapper in place.

Fig. 3 is a perspective view of the upper portion of the package with the handle in its lowered position.

Fig. 4 is a perspective view similar to Fig. 3, but showing the handle in raised position.

Fig. 5 is a sectional detail on the line 5—5 of Fig. 1.

Fig. 6 is a sectional detail on the line 6—6 of Fig. 2.

Fig. 7 is a plan view of the blank forming the base and side columns of the container.

Fig. 8 is a plan view of the blank forming the wrapper.

Fig. 9 is a perspective view of the handle.

Fig. 10 is a plan view of one of the interleaves between successive layers.

Fig. 11 is a perspective view of the clip to which the handle is attached.

Fig. 12 is a perspective view of one of the individual portions.

Fig. 13 is a perspective view of an alternative form showing a different form of wrapper partially in place.

Fig. 14 is a perspective view of a cover member and handle adapted for use in connection with the construction shown in Fig. 13.

Fig. 15 is a perspective view of the completed package.

Fig. 16 is a sectional detail on the line 16—16 of Fig. 15.

Fig. 17 is a sectional detail on the line 17—17 of Fig. 16.

Fig. 18 is a perspective view of the clip for connecting the cover, handle and side columns.

5 Fig. 19 is a plan view of a portion of another form of blank used in making the base and columns of the construction shown in Fig. 13, and

10 Fig. 20 is a perspective view of a portion of a package made from the blank shown in Fig. 19.

15 In the specific form shown in Figs. 1 to 12 inclusive, the container includes a base and two opposite side columns formed integral therewith and from comparatively stiff, but inexpensive sheet material, such as fiber board, but which is not so stiff but what it may be bent along scored lines. The blank from which is formed the frame comprising the bottom and side columns is shown particularly in Fig. 7. This includes a central or base portion 20 with extensions at opposite 20 sides adapted to be folded along scored lines 21 to form opposed parallel side walls 22. Each of these side walls have an extension at each edge thereof which may be folded along a scored line 23 to form a flange 24. At the end of each flange 25 nearest to the base 20, there is an extension which may be folded along a scored line 25 to form a flap 26, and at the outer or free end of the side wall 20 there is an extension which may be folded along a scored line 27 to form a flap 28. 30 The base has scored lines 29 adjacent to its side edges and between the side walls 20, whereby extensions may be folded upwardly to form flaps or flanges 30. The scored lines 29 may be at an angle of approximately 120° to the scored lines 35 21 so that when the side walls 22 and the flaps 30 are folded upwardly the base is left of approximately hexagonal form.

40 In forming the container the walls 22 are bent upwardly substantially at right angles to the base 20 to form opposed substantially parallel side walls, and the flanges 24 are bent inwardly to approximately an angle of 120° to the side walls. The flaps 26 are bent outwardly to lie parallel to and directly superposed on the base 45 20 and may be rigidly secured thereto in any suitable manner, as for instance, by wire staples 33. The fastening of these flaps to the base, holds the flanges 24 at the predetermined angle in respect to the side walls and likewise holds the side walls in their parallel vertical spaced positions.

50 The flanges or flaps 28 may be folded over into horizontal planes parallel to the base, and these flanges or flaps are preferably of greater length than the width of the side walls 22 so that the end portions may rest directly upon the upper ends of the flanges 24 and be supported thereby. The side walls together with their side flanges 24 form columns which are comparatively 55 rigid, and the flaps 28 form top walls on these columns so that when one package is placed upon another the weight of the upper package will be adequately supported by the columns of the lower one and will not be transmitted to the 60 contents of the lower package.

65 The frame work so far described may have the contents inserted with the parts in position described, or the contents may be assembled on the base, and the side walls thereafter bent to their vertical positions and secured by the fastening 70 members 33.

75 The frame is particularly adapted for use in the shipment and storage of individual portions of ice cream, such for instance, as is shown in Fig. 12. Each of these includes a cylindrical block

of ice cream 35 with a wrapper around the periphery and formed of two sections 36 of paper or other flexible sheet material. Each section extends around slightly more than one-half of the periphery of the block, and each has one edge terminating in a flap or extension 37. These two extensions are at approximately diametrical opposite sides so that by grasping the two extensions of the wrapper and pulling them in opposite directions, the two sections of the wrapper 10 are easily peeled off or removed from the body portion 35 without bringing the hands in contact with the material and without the use of special implements.

15 In making up the package a row or tier of the individual units, such as shown in Fig. 12, are placed on the base 20, but spaced therefrom by a suitable interleaf or sheet 38 of paper or analogous material which will protect the ends of the blocks 35 from direct contact with the base 20. 20 Above the first tier is placed other of the interleaves 38 and other tiers of the individual portions until the container is filled. It will, of course, be obvious that the order in which the portions of the contents are placed in position 25 is immaterial as the entire stack may be made up outside of the container and placed on the base before the side walls are bent up and fastened, or such a stack may be inserted between the side walls and while the flaps 28 are in vertical position. The individual units in each tier are advantageously arranged in concentric rows.

30 After the contents have been placed in position, the wrapper is brought into position around the contents and the side columns and to cover the top. In Fig. 8, I have shown a blank from which such a wrapper may be formed. This includes a body portion 40 which may have scored lines to divide it into six panels corresponding to the approximately hexagonal form of the 40 package and may have an adhesive coated flap 41 along one end whereby the body portion may be glued up in substantially tubular form. Each panel of the body portion has a flap or extension 42 at one end, and these are separated by slits 45 whereby all of the flaps may be folded over to form a cover as shown in Fig. 3. The flaps may be held down by a label 43 which may be pasted across the top and bear suitable marking or printing to indicate the contents or flavor of 50 the package. This wrapper, in the form of a tubular wall and top wall, is telescoped down over the assembled parts shown in Fig. 1, so as to completely enclose the contents and all portions of the frame except the base. The flaps 30 on the 55 base may be bent up into substantially vertical planes so as to prevent any foreign matter from entering beneath the lower edge of the wrapper during any lateral movement or sliding of the package on any supporting surface.

60 For carrying the package there may be provided a handle such as shown in Fig. 9. This includes a bar 45 of any desired cross-sectional form, and with flattened end portions 46 bent downwardly substantially at right angles and having slots 47 extending substantially lengthwise of these end portions 46. For attaching the handle to the columns, there may be provided a metal clip, such as shown in Fig. 11. This includes a base portion 50 which may lie against the inner or under side of the flap 28 and be secured thereto by a tongue 51 extending up through a slot 52 in the flap 28 and bent over into engagement with the upper surface as shown 70 in Fig. 5.

The clip has a flange 53 extending downwardly at right angles from one edge so as to lie closely adjacent to the inner surface of the side wall 22 and this flange has a pair of extensions or ears 54 bent outwardly therefrom in substantially parallel planes and adapted to pass out through an aperture 55 in the side wall 22 adjacent to the fold line 27. Two of the panels of the wrapper may be provided with apertures 56, and in placing the wrapper in position, these apertures are brought opposite the ears 54 so that the latter extend out through the wrapper as shown in Fig. 2. The handle may then be placed in position with the ears extending out through the slots 47 and the ears bent away from each other to engage the outer surface of the depending extensions on the handle and retain the handle in position. The slots 47 are so positioned and are of such length that the handle may normally lie flat against the top of the wrapper and will prevent the side walls 22 from spreading apart or being pressed together at their upper ends, and will form an additional strength element, whereby one package may more effectively support a superposed package.

When it is desired to transport the package, the handle may be moved upwardly due to the sliding movement permitted by the slots 47, and the handle will be spaced a sufficient distance above the top of the package so that it may be readily grasped as shown in Fig. 4.

When it is desired to open the package, the wrapper or upper portion thereof may be torn off with or without removing the handle. By leaving a part of the wrapper in place, the lower tiers of the contents will remain protected, but the individual packages may be removed from the top or upper portion. Successive portions of the wrapper may be torn away as the contents are dispensed.

It will be noted that such removal of the wrapper does not destroy the strength element of the container and will still permit a partially or entirely empty container to support the full weight of another package if such be desired.

The entire package may be made of approximately the diameter of an ordinary five gallon ice cream can so that it may be lowered into the wall of the refrigerating cabinet which was intended to receive such a five gallon can and the package may be of such height and the individual portions of such size that each package will contain the equivalent of approximately two and one-half gallons of ice cream, and two of the packages may be placed, one on top of the other, in the refrigerating cabinet. By entirely removing the wrapper before inserting the package in the cabinet the contents will be more directly exposed to the action of the refrigerating medium, such as cold air.

One advantage of my improved package is that, if it is desired that the contents be held at a relative high temperature with relation to the temperature at which the cabinet is being maintained, the wrapper may be left intact and thereby serve as an added insulator element between the portions and the refrigerated surfaces of the cabinet. On the other hand, if it is desired that the portions be maintained at a lower temperature, this outer wrapper may be stripped away so as to remove this insulating effect and thereby permit the portions within the container to reach a lower temperature.

The container is comparatively inexpensive and may be thrown away when the contents have

been used so that there is a very great saving over that involved in the use of metal cans which must be returned to the factory and thoroughly cleaned before refilling.

The ice cream in each layer is fully protected by the peripheral wrapper 36 and the upper and lower interleaves 38 so that it remains in a sanitary condition until dispensed. The interleaf above any layer may be pulled away a little at a time so as to expose only the individual packages which are to be immediately removed for use.

I do not wish to be limited to the specific construction illustrated, as various changes may be made in the details of construction. In Figs. 13 to 18 inclusive, there is shown a form which differs in some respects from that above described. Instead of forming the wrapper as a tubular body to be slipped over the frame after the contents have been placed in position, I may use a sheet 40a which may be scored the same as shown in Fig. 8, but which may have an edge portion 60 secured to one of the side walls 22. After the filling of the frame, the wrapper may be drawn tightly around the frame and its contents, and the opposite edge portion 61 then pasted or otherwise secured to the same side wall 22. This has the advantage in more firmly supporting the individual packages against any lateral movement and more effectively binding them in place than can be done with a loose wrapper telescoped into position. This wrapper therefore need not have any end flaps or form any cover to the package. In this construction I have shown a cover member 63 which may be approximately hexagonal in form with depending flaps 64 on pairs of opposite side edges. A flexible handle strip 65 of cloth or other analogous strong material may be permanently secured to the cover member and the cover member secured to the flaps at the upper ends of the side walls 22.

For accomplishing this purpose, I may employ a pair of clips such as shown in Fig. 18. Each clip includes a base portion 66 which may be applied directly to the upper side of the end portion of the handle. The base portion has side flanges 67 which may be forced down through the strip and through the cover 63 and bent into locking engagement with the under surface of the latter to lock the handle and cover together. Preferably, the handle strip 65 is folded around the edge of the cover to form an inner or under layer 68 through which the flanges 67 are projected as shown particularly in Figs. 16 and 17. The terminal portions of the flanges 67 may be bent inwardly so as to more firmly grip the parts together.

The base portion 66 has an upwardly extending flange 69 which may be extended through the slot 52 in the flap 28 after the cover is placed in position and the flaps 28 bent down onto the cover. This flange or tongue 69 may then be bent over toward the cover so as to hold the flap 28 down and to form a hook firmly engaging the flange 28 when the package is lifted by the handle 65.

In this construction, the handle is flexible while the cover is comparatively stiff and rests upon the upper ends of the flanges 24. Thus a superposed package rests primarily on the flanges 28 which are supported not only by the cover but by the side walls and the flanges 24. In opening this package, the edge of the flange 28 may be lifted up adjacent to one end thereof and such lifting movement will apply sufficient pressure on 75

the tongue 69 to straighten it up and permit the liberation of the flange and the lifting of the cover.

Between successive intervals of dispensing goods from the package the cover may be replaced, but does not need to be inserted beneath the flanges 28. It may be replaced directly over these flanges and properly positioned against lateral movement by the side flanges 64.

10 Figs. 19 and 20 show still another form of container in which the column or side portions 22a carry elongated flaps or flanges 28a which, in the finished package, rest on top of the cover 63a. The elongated flaps may be provided with a sub-flap 52a which may be cut out as shown. In this construction, the cover 63a is held in place by a gummed flavor label 43a which extends across the top and the ends of which may be adhesively secured to the opposite sides of the wrapper 40a. In the construction shown in these figures, the handle 65 may be dispensed with. It is obvious that the material from which the frame 22a is constructed should be sufficiently strong to support the weight of the contents of the package when same is being carried by the fingers which are inserted in the openings of one of the handles 28a.

It will, of course, be evident that various other modifications and changes may be made within the spirit of my invention and the scope thereof as defined in the appended claims.

Cognate subject matter is disclosed in my co-pending application Serial No. 709,245, filed February 1, 1934 and the invention common to this application and to said copending application Serial No. 709,245 is broadly claimed in the last mentioned application.

Having thus described my invention, what I claim as new and desire to secure by Letters 40 Patent is:

1. A container including a substantially hexagonal base of stiff sheet material and a pair of columns at opposite edges of said base, each column including a wall portion integral with said base and extending vertically therefrom, a pair of flanges integral with each wall at opposite side edges thereof and disposed in vertical planes at an angle of approximately 120° to the plane of the side wall and forming substantial portions of the other four walls, and means for securing the lower end of each flange to said base.

2. A container including a substantially hexagonal base of stiff sheet material and a pair of columns at opposite edges of said base, each column including a wall portion integral with said base and extending vertically therefrom, a pair of flanges integral with each wall at opposite side edges thereof and disposed in vertical planes at an angle to the plane of the side wall, each wall having a substantially horizontal flange at the upper end thereof, and a separate top wall between said columns and engaging the upper ends of said first mentioned flanges and overlapped by said second mentioned flanges.

3. A container including a base of stiff sheet material and a pair of channel-shaped columns at opposite edges of said base and extending vertically therefrom, said columns being formed integral with said base, and each column having

a substantially horizontal inwardly extending flange at the upper end thereof, a cover member between said columns and beneath said flanges, and limiting the inward movement of the upper ends of said columns, and a handle secured to said flanges.

4. A container including a frame having a substantially hexagonal base and a pair of columns at opposite edges thereof, each column including a wall portion integral with said base and extending vertically therefrom, and a pair of flanges integral with each wall at opposite side edges thereof and disposed in vertical planes at an angle of approximately 120° to the plane of the wall and forming substantial portions of the other four walls, means for securing the lower end of each flange to said base, a handle secured to the outer sides of the upper ends of said columns and holding said ends against inward or outward movement, and means independent of said flanges and said handle for limiting inward movement of the upper ends of said columns.

5. A container including a base of comparatively stiff sheet material and a pair of opposite upwardly extending side walls integral therewith, outwardly extending lugs at the upper ends of said side walls, a wrapper encircling said side walls and having apertures through which said lugs extend, and a handle secured to said lugs. 30

6. A container including a base of comparatively stiff sheet material and a pair of opposite upwardly extending columns integral therewith, outwardly extending lugs at the upper end of said columns, a wrapper encircling said 35 columns and having apertures through which said lugs extend, and a handle secured to said lugs, said handle being vertically movable through a predetermined and limited distance in respect to said columns.

7. A container including a base and a pair of columns extending upwardly from opposite side edges thereof, each column having an inwardly directed flange at its upper end, said base, columns and flanges being formed from a single 45 piece of stiff sheet material, a separate, comparatively stiff cover between said columns at their upper ends, and limiting the inward movement thereof, and a flexible handle having the opposite end secured to said flanges. 50

8. A container including a base and a pair of columns extending upwardly from opposite side edges thereof, each column having an inwardly directed flange at its upper end, said base, columns and flanges being formed from a single 55 piece of stiff sheet material, a cover member adapted to be disposed beneath said flanges, and clips for securing said handle to said cover and securing said cover to said flanges.

9. A container including a base, side walls 60 extending upwardly from two opposite edges thereof, and each having side flanges secured at their lower ends to said base, said base, walls and flanges being formed from a single sheet of comparatively stiff material, a wrapper of tubular form adapted to telescope over said side walls and the contents of said container, and having a top wall, and a handle above said top wall and detachably secured to the upper ends of said side walls. 65

CLARENCE W. VOGT. 70
